G. H. RICKE

SPARK PLUG FOR AUTOMOBILES

Filed Aug. 2, 1922.

FIG. 2

FIG. 1

FIG. 4

FIG. 3

FIG. 5.

INVENTOR.

George H. Ricke
John W. Trebil

ATTORNEY.

UNITED STATES PATENT OFFICE.

GEORGE H. RICKE, OF CINCINNATI, OHIO.

SPARK PLUG FOR AUTOMOBILES.

Application filed August 2, 1922. Serial No. 579,845.

To all whom it may concern:

Be it known that I, GEORGE H. RICKE, a citizen of the United States, residing at the city of Cincinnati, in the county of Hamilton and State of Ohio, have invented certain new and useful Improvements in Spark Plugs for Automobiles, of which the following is a specification.

The primary object of the present invention is to provide a spark plug which will not become foul or inoperative during use. It is a well known fact that the inner end of the ordinary spark plug, extends into the combustion chamber of an engine cylinder, and as this end of the spark plug is usually open, oil splashes on the same and carbon is formed, which eventually insulates the electrodes to such an extent, that they no longer produce a spark. As a result the cylinder containing the foul plug, ceases to produce power.

My improved spark plug is so constructed that oil splashing within the cylinder is prevented from reaching the electrodes, and the plug has apertures to permit the circulation of the explosive mixture and the gases resulting from explosions, through the chamber of the spark plug for the purpose of cleaning the electrodes.

30 In the accompanying drawing, forming part of this specification:

Fig. 1, is a view of a spark plug in elevation, partly broken away, and in section to show my invention,

35 Fig. 2 is an elevation of the same viewed from another side.

Fig. 3, is a section on line 3—3 of Fig. 1.

Fig. 4, is an enlarged bottom view.

40 Fig. 5, is a vertical section of the lower end of a spark plug, with my invention applied thereto in a modified form.

In the drawing, the spark plug itself, or the body thereof is marked 1. My invention consists in adding to the body 1, a cylindrical skirt 2, provided at its mouth with a baffle disk 3, having arms 4, which join it to the cylinder 2, thus forming apertures at 5. In Fig. 5, however, cylinder 2 is made integral with the disk 3, having a slot opening 5.

At one side the cylinder 2 is provided with a port 6.

The usual terminal wire or electrode 7, is employed and I also employ a wire or elec-

trode 8, one positive and the other negative, so that when the electric current is applied, a spark is created between them.

My new spark plug operates efficiently and does not gather carbon or oil. Consequently less oil and plugs are used, less cleaning is necessary, and the engine remains in a more perfect condition at all times, delivering all power expected from all its cylinders and pistons; inasmuch as I keep the inside of the spark plug dry so that it can spark perfectly.

The port 6 is on the inside of the compression or combustion chamber when the spark plug is put in place, so that when there is an explosion free circulation for the gaseous products is insured, as these pass out thru said port 6 and thru the apertures 5 leaving no chance for carbon or other deposits on the inside of the spark plug and on the electrodes.

75 The disk 3 can be made integral with the cylinders 2, or may be attached if desired.

My invention can be used in connection with any form or style of spark plug and I do not confine myself to the specific construction herein shown in carrying out my invention, the form shown being a preferred one.

What I claim as new and my invention and desire to secure by Letters Patent is:

85 A spark plug including a shell provided with external threads adapted to engage the threads of an engine cylinder and having a skirt projecting beyond the threaded portion and adapted in practice to extend into the engine cylinder with which the plug is used, a baffle arranged at the lower end of said skirt portion and adapted to prevent oil and the like from entering said skirt, said plug being provided with a lower aperture between the skirt and baffle, a port provided in the skirt near the upper end of the same, a central electrode arranged in said shell and a second electrode in electrical connection with said skirt, said electrodes being arranged within the shell between the upper and lower apertures, whereby a circulation of gas may take place past said electrodes.

100 In testimony whereof, I affix my signature at Cincinnati, Ohio, this first day of August, 1922.

GEORGE H. RICKE.
